UNITED STATES PATENT OFFICE.

CHARLES O. KEAGY AND JAMES R. CARMER, OF WILMINGTON, DELAWARE.

MAIL-BOX.

1,096,724.

Specification of Letters Patent. Patented May 12, 1914.

Application filed April 23, 1912. Serial No. 692,621.

To all whom it may concern:

Be it known that we, CHARLES O. KEAGY and JAMES R. CARMER, citizens of the United States, residing at Wilmington, in the county of Newcastle and State of Delaware, have invented new and useful Improvements in Mail-Boxes, of which the following is a specification.

This invention relates to a holder or letter box for mail matter, newspapers and other articles, and consists essentially of a support or backing having a gravitating front or holding member coöperating therewith and expansible relatively to the support or backing when manually elevated to increase its capacity within predetermined limits or in accordance with the dimensions of the device as a whole, the front or holding member having thereon a letter receiving receptacle wherein letter mail may be protectively deposited and freely movable with the said front or holding member during the operation of disposing newspapers, magazines and other large parcels between the support or backing and the member. The invention further consists in the construction and arrangement of the several parts which will be more fully hereinafter described and claimed and constitutes an improvement on the holder or letter box disclosed by our application filed April 17, 1911, Serial No. 621,614.

The purpose of the improvements is to provide a simple or effective holder or letter box for mail matter arranged to receive newspapers, magazines and other analogous parcels in one portion thereof and letters and like mail matter in another part of the same and to embody in one organization means which are readily accessible for deposit and removal of mail matter of different kinds in an expeditious and convenient manner and with special advantages to the owner of the mail box or recipient of the mail matter disposed therein.

In the drawings: Figure 1 is a perspective view, partially broken away, of a holder or mail box embodying the features of the invention and illustrated and being fully closed. Fig. 2 is a side elevation of the mail box partially broken away and shown open and containing different kinds of mail matter, the letter receiving attachment or inclosure applied to the front member being illustrated in open position in dotted lines. Fig. 3 is a front elevation of the box broken

away and illustrating a modification. Fig. 4 is a horizontal section taken in the plane of the line 4—4, Fig. 3.

The numeral 5 designates a support which may be a wall, side of a house, post, or other structure, or said support may be constructed as a panel adapted to be secured to or hung on any other main supporting means. Fixed to the support 5 is a backing or rear side 6 of the holder or box, said backing being formed with side flanges 7 extending full length thereof and projecting below the lower edge of the backing to provide attaching means or eyes 8. The backing 6 is preferably secured to the support 5 by fastening devices inserted through the same between the flanges 7, said fastening devices being shown in the present instance as screws 9, though other devices might be used if so desired. Movably connected to the backing or rear side 6 of the holder or box is a bottom section 10, see Fig. 2, which is similar in its construction to the said backing or rear side and has side flanges 11 which are projected at opposite ends as at 12 and 13 for convenience in movably associating the said section with the lower ends of the flanges 7 and with the front holding member 14 also formed with side flanges 15 projected at their lower ends as at 16 to provide means for attaching the similarly projected ends of the flanges 11 of the bottom section 10. The front side or main holding member 18 is also connected to the flanges 7 of the backing by links 17 which have their inner ends applied against the outer side flanges 7 and their opposite outer ends applied against the inner sides of the flanges 15 of the front member 18 at a suitable distance from the upper end of the said front member. The front member 14 with its flanges 15 has a greater width than the backing or rear side 6 and folds over the latter and also over the links 17 and the side flanges 11 of the bottom section 10 when the latter is fully closed down. The front or holding member 14 is also formed with a plurality of openings 18, as shown by Fig. 1, to assist in applying the fastening devices 9 which are inserted through the backing 6 into the support 5. The front or holding member 14 is restricted in its upward movement by the links 17 which have their outer ends attached to the flanges 15, the said links having their outer ends projected beyond the fulcrum points thereof and squared as at

19, see Fig. 2, to contact with the inner surface of the said front or holding member adjacent to the points of intersection of the flanges 17 therewith.

5 Over the outer side of the front or holding member 14 a box or letter inclosing member 20 is applied and provided with side flanges 21 and a lower suitably curved extremity 22 which is hinged as at 23 to the lower edge of the said front or holding member 14, as shown by Figs. 1 and 2; or as shown by Figs. 3 and 4 the said box or letter inclosing member 20 may be hinged at the side as at 24, and in which case it 10 will be provided with an inwardly extending bottom flange 25. The side flanges 21 in both forms of application of the box or letter inclosing member 20 are extended inwardly as protecting or sealing flanges 26 15 and formed with longitudinal beads 27 to fit corresponding grooves or seats 28 in the front or holding member 14; the beads and recesses providing tight joints at opposite sides of the coöperating box or letter inclosing member 20 and the front member 14 to prevent the letters or mail matter from slipping through open crevices at the opposite sides of the front portion of the device 20 and also to obstruct the entrance of water 25 or moisture into the box formed on the front of the device. The front or main holding member 14 together with the box or mail inclosing member 20 constitutes a movable box adjustably held by the backing or 30 supporting member 6, and in the construction shown by Figs. 1 and 2 the main holding member 14 has an upper outwardly projecting guard flange 29 under which the upper open extremity of the box or mail inclosing member 20 is adapted to closely fit, the guard flange 29 having depending end flanges 30 to shield the upper side portions 35 of the box or mail inclosing member 20 and particularly the flanges 21 thereof. On the outer side of the upper end of the box or inclosing member 20 the usual form of mail box lock 31 is applied and coöperates with a striker 32 secured to the under side of the flange 29, and in the side opening form of 40 the box or inclosing member 20 as shown by Fig. 3 a similar lock 33 is secured thereto adjacent to the side opposite that which is hinged and coöperates with a striker 34 projecting from one of the side flanges 15, the latter flange being extended outwardly a 45 greater distance, as shown by Fig. 4, as at 15, to provide a shield or guard for the adjacent side flange 21 of the box or inclosing member 20 and to place the striker 34 in proper position relatively to the lock 33. To limit the outward movement of the box or letter inclosing member 20, links 35 are shown by Figs. 1 and 2, the said links being pivoted at their lower ends to the flanges 21 50 and at their upper ends formed with slots

36 and engaged by headed studs 37 fixed on the flanges 15. This form of limiting means for the movement of the box or mail inclosing member 20 may, however, be indefinitely varied and in some instances the use thereof 70 may be unnecessary, the only object in applying the links 35 or other limiting devices being to prevent the box or mail inclosing member 20 from falling completely over, which would be unnecessary to gain access 75 to the mail matter or letters held between the said member 20 and the member 14.

In the modified structure shown by Figs. 3 and 4 the same flanges 26 having the beads 27 engaging the grooves 28 are employed at 80 the opposite sides of the box or mail inclosing member 20, and in addition the bottom or lower end of the box or mail inclosing member as shown by Figs. 3 and 4 has an upwardly projecting flange 38 with a bead 85 and corresponding groove, as indicated by Figs. 3 and 4, as at 39 and 40.

In the operation of the device or when it is desired to dispose newspapers, magazines and other parcels between the main holding 90 member 14 and the backing 6, the said holding member is elevated by pressing upwardly on the lower end thereof, the upward movement of the holding member being proportionate to the thickness of the 95 newspapers, magazines or other parcels adapted to be inserted in the box and to render such operation easy without friction in a predetermined capacity. After newspapers, magazines or other parcels have 100 been disposed in the device between the main holding member 14 and the backing 6 the said member will be released and allowed to gravitate, thereby setting up a binding action on the papers, magazines or 105 parcels, and as the said main holding member has considerable weight, particularly in view of the application thereto of the box or mail inclosing member 20, the papers, magazines or other parcels will be positively and reliably retained or clamped between the member 14 and backing 6 and be 110 prevented from falling through the bottom of the device by the then projected bottom section 10 which regularly moves outwardly 115 in proportion to the elevation of the said member 14. Letters or analogous mail matter may be inserted into the front portion of the device or between the member 14 and the box or mail inclosing member 20 through a customary form of drop slot 41 which may or may not be covered by the usual drop shield. When it is desired to remove the mail matter from the device the main member 14 with the box or inclosing member 20 is pushed upwardly to relieve pressure on or relax the clamping weight on the papers, magazines or other parcels between the member 14 and backing 6 and the 120 said papers, magazines or parcels may then 125 130

be readily withdrawn from the top of the device and the member 14 with its member 20 permitted to gravitate. The box or inclosing member 20 may, at any time, be released and opened to permit access to the letters deposited between the same and the holding member or in the box itself on the front of the device and afterward closed and locked. When the main holding member 14 together with the box or mail inclosing member 20 is fully closed or is gravitated and the bottom section 10 has moved backwardly, and unobstructed opening through the entire length of the rear portion of the device is provided and any moisture or dust that may enter the box will pass downwardly through the same, thus keeping the interior of the box in dry and clean condition.

20 It will be understood that the proportions, dimensions and minor details of the improved device may be varied at will within the scope of the claims, and, furthermore, it is proposed to use the same for any purpose 25 to which it may be applicable.

What is claimed is:

1. In a device of the class set forth, a support, a gravitating box-like holding member attached to the support and automatically 30 projected from the latter when elevated, the said member being provided with a front side which is closed to such an extent as to prevent mail matter passing therethrough, and a letter inclosing body with angular

side and end members, an outer closed side, 35 and a back which is normally fully open, the inclosing body being hinged to the outer or front side of the holding member and closed at the rear by the said member, the letter inclosing body being also provided 40 with inwardly extending sealing flanges which bear flat against the outer side of the holding member and movable with the said body in the opening and closing movements of the latter. 45

2. In a device of the class set forth, a holding member for papers, magazines and parcels, and a letter inclosing member on the outer side of the holding member and provided with inwardly extending sealing 50 flanges which bear flat against the outer side of the holding member.

3. In a device of the class set forth, a holding member for papers, magazines and parcels having grooves formed in its outer 55 side, and a letter inclosing member on the outer side of the holding member and provided with inwardly extending sealing flanges formed with beads to engage said grooves. 60

In testimony whereof we have hereunto set our hands in presence of two subscribing witnesses.

CHARLES O. KEAGY.
JAMES R. CARMER.
